UNITED STATES PATENT OFFICE.

CHARLES E. YETMAN, OF OAKPARK, ILLINOIS.

TELEGRAPHIC TRANSMITTER.

SPECIFICATION forming part of Letters Patent No. 692,967, dated February 11, 1902.

Application filed February 8, 1901. Serial No. 46,580. (No model.)

To all whom it may concern:

Be it known that I, CHARLES E. YETMAN, of Oakpark, Cook county, Illinois, have invented certain new and useful Improvements 5 in Telegraphic Transmitters, of which the following is hereby declared to be a full, clear, and exact description.

My invention relates to improvements in electric code-transmitters of the type which 10 are operated by finger-keys similar to those of an ordinary type-writer and such as are disclosed in my United States Letters Patent No. 534,025, dated February 12, 1895, and more particularly to such transmitters as are 15 combined with a type-writer the operation of which is governed from the same keys, such as are disclosed in my United States Letters Patent No. 565,128, dated August 4, 1896.

The details of the preferred form of the 20 device are set forth in the following description and illustrated in the accompanying drawings, and the invention is particularly pointed out by claims at the end of the specification.

25 In the drawings, Figure 1 is a longitudinal section through the combined type-writer and transmitter from front to rear, one key-lever and the attached parts being shown in full lines. Figs. 1^a and 1^b are detail views of a 30 part of the operating mechanism shown in different positions. Fig. 2 is a partial horizontal section on line 2 of Fig. 1 looking in the direction of the arrow and illustrating the details of the transmitter. Fig. 3 is a 35 vertical detail sectional view through the front part of the machine, showing the connectors between the finger-keys and the "switch-shifters" of the transmitter. Fig. 4 is a sectional view of the transmitter, looking 40 in the direction of the arrow, on line 4 of Fig. 2. Fig. 5 is a sectional view, looking in the direction of the arrow, on line 5 of Fig. 2. Figs. 6 and 7 are detail views of one 45 of the switch-shifters of the transmitter. Figs. 8 and 9 are sectional views, looking in the direction of the arrow, on lines 8 and 9 of Fig. 4, respectively, with the central portion omitted. Figs. 10 and 11 are front 50 and rear elevations, respectively, of the transmitter with certain portions omitted. Fig. 12 is a sectional view, looking in the direction of the arrow, on lines 12 of Fig. 2.

The drawings illustrate the invention as

applied to a style of "sight" type-writer such as is disclosed in my applications for Letters 55 Patent filed by me in the United States Patent Office September 26, 1900, Serial Nos. 31,198 and 31,199; but it will be understood that the improvements are not confined to this particular style and can be applied to various 60 forms of type-writers without essential departure from the invention.

The base-frame 10 is of the usual rectangular form and is furnished with rubber plugs or feet 11, upon which the machine rests. 65 Upon the base are mounted the plate 12 and the upper portion 13. This upper portion sustains the carriage grooved tracks 14 and 15, which, by means of the grooved rails 16 and 17 and balls 18, support the paper-carriage 70 19. Suitably journaled on the paper-carriage is the platen 20. The carriage and paper-feed mechanisms form no part of the present invention and are not shown or described. A semicircular stepped support 21, secured 75 to the front of the upper portion 13, serves as a mount for the type-bars 22, set in circular range about the same and pivoted to the separate lugs 23 therefor. The rest-pad 24 for the type-bars is carried by a support 25, secured 80 to the plate 12. Links 26 are pivoted to and extend below the type-bars 22 and connect the latter to the key-action. The finger-keys 27 are of the usual lever form and are arranged in regular series or banks across the 85 front of the machine and extend back in parallel relation to the fulcrum-ledge 28, which is suitably secured to a strip 29, extending across the frame 10. The key-levers are provided with upwardly-projecting offsets 30, between which and the strip 29 extend the 90 springs 31 to hold the levers in their normal uplifted position in readiness to be struck by the operator. The usual space-bar 32 and universal bar 33 are also fulcrumed on the 95 ledge 28, and the universal bar is arranged to operate a suitable escapement (not shown) for the paper-carriage. A buffer 34 is arranged across the machine above the key-levers, against which the latter strike when released. 100

Interposed between the key-levers and the type-bars is a supplemental structure by which the type-bars may be thrown out of action.

As will be presently shown, the key-levers

serve to actuate both the bars of the type-writer and the switch-shifters of the transmitter. Although these devices are frequently used in unison, by which means a verifying copy of the message transmitted will be written, yet occasions frequently arise when it is desirable to operate either the transmitter or the type-writer separately or to throw either or both devices out of operation—as, for example, when the operator temporarily leaves his work—so that the machine will not respond to accidental or mischievous operation of the finger-keys. For these reasons a series of supplemental levers 35 are interposed between the key-levers 27 and the links 26. The levers are pivoted on the fulcrum-bars 37 and 38, are pivotally connected at their upper ends to the links 26 of the type-bars 27, and are provided with laterally-projecting pins 39, which are engaged in slots or seats in the upper part of offsets 30. It is obvious that if the supplemental bars be raised so that the pins 39 will clear these slots or seats, then the depression of the key-levers 25 will produce no movement of the supplemental levers or of the type-bars. I prefer to employ the mechanism next to be described for effecting this result.

Through the frame 10 extends a shaft 40, provided on its outer end with an operating-handle and inside the frame with cranks 42, which are connected by links 43 with toggles 44. One end of toggles 44 is pivoted to the fulcrum-bar 37 and the other to the depending brackets secured to bar 28. The pivot-bars 37 and 38 are connected together by suitable bolts 45, that pass through guide-sleeves 46, mounted in the central pivot-bar 28. In Figs. 1 and 1^b the parts are shown in normal position, with the pivot-pins 39 in engagement with the seats on offsets 30. If, however, the parts are shifted by shaft 40 into the position shown in Fig. 1^a, the pivot-bars 37 and 38 and supplemental levers 35 will be bodily moved to the pins 39 from engagement with the offsets 30 and the type-bars will not respond to the play of the key-levers 27. By reference to Fig. 1^b it will be seen that the toggles 44 are shifted slightly beyond the line of centers, so that they serve to temporarily hold the pivot-bars and supplementary levers in raised position.

Toward the front of the machine each key-lever 27 carries pivoted thereto, as at 47, a connector 48, having a side pin 49, designed to encounter the toe 50 of the switch appliance or shifter F, extending into the path thereof. The parallel set of connectors 48 are provided with slots 51, all of which are engaged by a throw-off 52, which consists of a transverse metal rod and sliding comb-bar 52^a, sustained at its ends by cranks 53, mounted on trunnion-shaft 54, whereby the throw-off may be shifted to bring the studs 49 into or out of range with the toes of the parallel series of shifters F on the transmitter. On one end of the shaft 54, which extends

through the side of the machine, is secured the actuating-handle 55. A cam-spring 56 is secured to the side of frame 10 and is provided with an angular cam-surface 57, which engages a similar cam-surface 58 on an arm 59, secured to shaft 54. The operator will operate the handle 55 to move the parts until the point of the angular cam-surface 58 is passed beneath that of cam-surface 57, which cam-surfaces will then operate to force and lock the parts either into or out of the operative position.

Secured inside of the frame 10 by means of screws 60 passing through bosses 61 are the side frame-pieces A A' of the transmitter, which is thus free to be attached to or detached from the type-writer proper, as desired. The side pieces A A' are preferably of insulating material—e. g., vulcanized fiber—and in suitable recesses therein are located the hub-boxes a' of the fluted shaft B. Shaft B extends across the machine and affords a mount for the set of switch appliances such as are requisite to transmit a complete system of conventional code-signals. At one end (see Figs. 2 and 8) the shaft B carries a pinion b', usually of vulcanized fiber, and which engages with the gear-train (not shown) of a suitable motor designed to drive the shaft at uniform speed.

A series of shifters F in the form of levers and designed to control the diversion of the electric current through any of the several switches or symbol-disks appropriate to the individual signals in the code system is mounted in parallel array near the lower part of the transmitter-frame. The several shifters are pivoted to the comb-bar 62, secured at the rear to the side frame-pieces A A', and extend through the downwardly-projecting teeth 63 of the bar 64, secured to the front of the transmitter-frame. By the teeth 63 the free ends of the switch levers or shifters are held in position and have a limited play between the buffer-strips 65 and 66 of the transverse bars 64 and 67, respectively. Springs 68 extend between the shifters F and the transverse bar 69 and hold the former in normal relation snugly against the buffer-strip 65 and in position for stud-pin 49 on connector 48 to strike the toe 50 of the adjacent shifter F and depress the shifter against the stress of spring 68 if the suitable key-lever be brought into play.

On the rotating driver B is mounted the series of symbol disks or rings E, the inner rims of which are fluted to engage at will with the fluted driver. On the outer rim of the several metal rings E are insulatory blocks e at proper intervals. The insulation varies in keeping with the conventional signal for the letter, character, or word to be transmitted by the particular ring. The drawing Fig. 4 shows a ring designed to send one dash and two dots, which by the Morse code signifies the letter D. It is also apparent that the ring referred to has the signal dash and dots

repeated three times about its periphery. Space-pins e' project from the ring-rim between each signal set. These are preferably set in insulating-plugs of rawhide and serve 5 as trips to check the motion of the ring at the insulation-block on completion of the signal, as presently set forth.

Ordinarily the circuit-rings E stand disengaged from the driver B, but rest instead 10 upon the shifters, which are provided between their ends with a curved portion, to either side of which are secured strips 69 of insulating material—*e. g.*, vulcanized fiber—which are of rounded contour to conform to the ring- 15 rim. In such shape the shifters act as a brake to quickly arrest the revolution of the ring on release from the driver. The strips 69 furnish a broad seat for the ring and proper 20 clearance for the space-pins e' on the ring, which are conveniently set on the median line 25 of the rim. In order to separate the rings, thin insulating-strip 70 is secured in one side of each of the shifters, and its upper edge is straight, so that the entire series of shifters, 30 with the insulating-strips, forms a series of recesses in which the symbol-disks rest and by which they are held apart. Under stress 35 of the springs 68 the shifters F generally stand in uplifted position and carry with them the series of circuit-rings, which are thus free 40 from the driver B and do not revolve.

The transverse bar 64 is provided on its inner face with notches, in which are pivoted the upper members m of the toggle-latches 45 by means of a common pivot-rod P^2 . The lower members m' of the toggle-latches are pivoted to the members m and by a pin-and-slot connection to the forward ends of the shifters F. Coiled springs P are fastened to 50 a common rod P' , extend through openings in the bar 64, and are attached to the members m of the toggle-latches. These toggle-latches are held in their normal flexed position (shown in Fig. 1) by the upward pressure of 55 the shifters under stress of the springs 68. When any particular shifter is depressed, the toggles are straightened and drawn into a position somewhat beyond the line of centers by the springs P, (see Fig. 4,) so that 60 the shifter is locked in its depressed position. At the same time the trip-pawl g' , which is pivoted at the upper end of lever m , drops accordingly against the face of the circuit-ring E and rests in the path of the space-pins 65 e' . The descent of the shifter necessarily lowers the circuit-ring E, which it controls, and brings such ring into engagement with the rotating driver B. At once the circuit-ring begins to revolve and so persists for a distance sufficient to transmit the desired signal.

When the transmitter is in use, the electric circuit can be traced from the battery (not shown) by wire 71 and binding-post 72, Figs. 2 and 10, wire 73, to binding-post 73^a, to the 75 transverse metallic comb-bar 74, which is secured at the rear of the transmitter to the insulating side walls A A'. The bar 74 car-

ries a series of contact-pieces u u' , brought to bear lightly upon the several circuit-rings E. When the metal part of the ring makes 70 contact with the contact-pieces u u' riding thereon, the circuit is closed thereby and may be traced further from the ring E, driver B, spring 75, pressed in contact at one end thereof, binding-post 76, line-wire 77, binding-post 75 78, and line-wire 79 to the distant station. To further insure the completion of the circuit, a wire 80 connects the binding-post 76 with the metallic hub-box a' of the driver B. The successive dots and dashes to complete 80 the signal are produced by the variations in lengths of the metallic parts of the ring having the insulation-blocks between them. As the signal is finished the next space-pin e' on the ring E encounters the trip-pawl g' and 85 forces it backward, thereby rocking the upper member m of the toggle-latch until its lower end has passed the line of centers. The shifter is then free to rise again to its normal position under stress of the spring 68, 90 and in rising it lifts the circuit-ring E out of engagement with the shaft B, arrests its motion, and forces the toggle-latch back into its normal position, while a lug or projection m^2 on lever m engages the pawl g' and raises it 95 clear of the ring. The parts are thus all returned to the normal state in readiness to allow for transmission of the next character or, as may be requisite, to repeat the same character.

In order to insure that the trip-pawl g' will always drop into contact with the ring E and to prevent it from being thrown back out of its normal position, the lever m is provided with a lug or projection m^3 similar to lug m^2 105 above the trip-pawl g' .

If multiple repetitions of the same character are desired, as in calling a distant station, this can be accomplished by holding the trip-pawl g' out of action clear of the path of the 110 space-pins on the circuit-ring E. A transverse pivot-bar W, arranged at one side and above the rings, carries the offset rod x, which will swing in the path of the series of pawls g' . The button y is threaded onto the end of 115 bar W and, extending through one side of the machine-frame, Fig. 2, serves to turn said bar, and thus bring the offset rod x in position to prevent the pawls g' from dropping into contact with the rings E. Hence when the selected shifter is depressed and held down by 120 its latch the individual pawl g' pertaining to the toggle-latch must stay uplifted, by which expedient the circuit-ring E continues to revolve on the driver B until the rod x is withdrawn at the will of the operator to allow the pawl g' to descend and effect the release of the latch, shifter F, and ring E. A locking-cam 81 is located in a depression in the inner 125 side of the frame-piece A and is secured to the bar W. The movement of the rods W and x is limited by the stop-pin 82, secured to frame-piece A and engaging a depression 83 in cam 81. Cam 81 is also provided with two annu-

lar notches 83, adapted to be engaged by an angular projection 84 on spring 85, secured to frame-piece A, by which the bar W together with its cross-rod x are held in their assigned position.

The contact-pieces u u' are arranged in pairs, both pieces of each pair engaging a single contact-ring. Between each pair is a shoulder-pin u², to which the contact-pieces 10 are loosely connected, light springs 86, extended between these pins and pins 87, connecting the insulating-pieces on the shifters F. One of each pair of contact-pieces has secured at its end a piece u³, of insulating material, which projects downwardly to a slight extent between adjacent rings E and serves to space their upper edges apart. By providing two contacting-pieces for each ring, which are to a slight degree independently 20 movable, I insure that the contact between the pieces and the metal parts of the rings will not be broken by the presence of particles of dust, &c.

It will be seen that ring E, if the springs 86 25 were fastened to a fixed part, would necessarily be raised against the pressure of these springs; but by securing them to the shifters F and arranging the parts so that little pressure will be exerted by springs 86 in the normal position tension will be placed upon these 30 springs 86, when the particular shifter is depressed at just the time when such a tension is required; but as soon as the shifter F commences to ascend this tension is relieved and 35 the ring E is easily lifted by the stress of spring 68 on shifter F. For this reason the springs 68 may have comparatively little tension, and therefore since the keys act in opposition to these springs the instrument will 40 quickly respond to the operator's touch.

As clearly shown in Fig. 1, the length of the finger-keys varies from the shortest in the highest bank of keys to the longest in the lowest bank, while the connectors are all pivoted to 45 the finger-keys at a uniform distance from the fulcrum. If, therefore, the contact-pins 49 are all located at the same distance from the pivots 47, it is evident that the depression of the finger-keys of the keyboard would be uneven. 50 To remedy this difficulty, the distances from the pivots 47 to the contact-point between the connectors 48 and the shifters F is varied in proportion to the length of the levers by varying the distance of the pins 49 from the pivots 47. By reference to Fig. 3 it will be seen that these pins are located at four different points 49^a, 49^b, 49^c, and 49^d, the connectors of the shortest key-levers having pins located at 49^a and those of the longest having pins 55 located at 49^d, while the connectors of the levers of intermediate lengths have contact-pins located at 49^b and 49^c. This arrangement will insure the proper actuation of the shifters of the transmitter while allowing the 60 same extents of downward movement to the forward ends of the key-levers regardless of

their length—i. e., it insures a uniformity of "touch" for the keys. The same result could be accomplished by placing the pins 49 at a uniform distance from the pivots 47 and placing lugs of varying heights on the toes 50 of the shifters F.

Provision is made for the arrest of the rotating driver B and to establish a short circuit around the machine. The end ring D' of 75 the series of rings, Figs. 5 and 8, is entirely of metal and is provided with a brake-surface 88, which is adapted to bear on the reduced portion 89 of the driver B. The locking-ring D' is provided at its top with a projecting lug 90, 80 to which are pivoted on either side the connecting-pieces 91, which are likewise pivoted to the transverse circuit-bar 74. The shifter F' to control the locking or short-circuit ring is mounted as usual and is provided with a 85 heavy spring 86^a, which forces the brake-surface 88 of the ring D' against the reduced portion 89 of the shaft B when the shifter F' is depressed. The result is to stop the rotation of the shaft B and close the circuit from bar 74 90 through ring D', shaft B, spring 75, and through its hub-box a', Fig. 8. To depress the end of the shifter F', the rock-shaft 54 carries a stud 92 on a projection 93 of one of the cranks 53, which stud bears against the toe of the 95 shifter F', and thus forces the shifter down when the handle 55 is manipulated by the operator to throw the connectors 48 out of operative position.

It may be desirable to complete the line-circuit through the machine without stopping the rotation of the driver B or without throwing the connector 48 out of operative position—as, for example, when the operator is interrupted for a few seconds. For this 105 purpose the studs 94 and 95 are mounted in insulating-sockets 96 and 97 in the side of the machine and connected by wires 98 and 99 with the binding-posts 78 and 72. Stud 94 is provided with the switch-lever 100, which is 110 adapted to engage the spring-contact surface 101 of stud 95.

Obviously the details of my invention can be varied according to the skill of the mechanic without departure from the essentials 115 of the invention.

Having thus described my invention, what I claim as new, and desire to secure by Letters Patent, is—

1. The combination with the series of transmitter switch-shifters, of a series of individual finger-keys of varying length corresponding thereto and having operating connections therefor, the lengths of which connections vary in accordance with the lengths of the 120 corresponding finger-keys.

2. The combination with the individual finger-keys of varying lengths and with the series of transmitter switch-shifters corresponding thereto, of the connectors extending from 130 said finger-keys and engaging with said shifters, the position of the points of engagement

between said connectors and shifters varying in accordance with the varying lengths of the corresponding finger-keys.

3. The combination with the individual finger-keys of varying lengths and with the series of transmitter switch-shifters corresponding thereto, of the set of connectors extending between said keys and shifters and having offsets for engaging said shifters, the location of said offsets upon the connectors varying in accordance with the varying lengths of the corresponding finger-keys.

4. The combination with the individual finger-keys of varying lengths and with the series of pivoted transmitter switch-shifters corresponding thereto, of the set of connectors pivoted to said finger-keys and provided with offsets adapted to engage the free ends of said shifters, the distances between the pivots and offsets of said connectors varying in accordance with the varying lengths of the corresponding finger-keys.

5. The combination with the series of transmitter switch-shifters, of a series of individual finger-keys corresponding thereto and having operating connections therefor, and a set of toggle-latches for holding said shifters out of normal position when actuated by the finger-keys.

30 6. The combination with the individual finger-keys, and with the series of transmitter switch-shifters corresponding thereto, of the set of connectors extending between said keys and shifters, whereby said shifters are depressed, and the set of latches for holding said shifters depressed, each of said latches consisting of toggle-levers one of which is pivoted to a fixed part and the other to the appropriate shifter.

40 7. The combination with the individual finger-keys and with the series of transmitter switch-shifters corresponding thereto, of the set of connectors extending between said finger-keys and said shifters, whereby the latter are depressed, and the set of toggles extending between a fixed part and said shifters for holding the shifters in the depressed position.

8. The combination with the individual finger-keys and with the series of transmitter switch-shifters corresponding thereto, of the set of connectors extending between said finger-keys and said shifters for actuating said shifters, the set of toggles extending between a fixed part and said shifters, for holding the latter out of normal position when actuated by the finger-keys, and trip-pawls for throwing said toggles to restore the selected shifters to their normal position.

9. The combination in an electric transmitter, with a series of switch-shifters and with a rotating shaft having circuit make and break devices thereon, of a set of toggles engaging with said shifters to hold them depressed, trip-pawls carried thereby and projected by the descent of said shifters into the path of said make and break devices, and engaging at intervals therewith to throw the

separate toggles and restore the shifters to their normal position.

10. The combination, in an electric transmitter, with a series of switch-shifters, of a set of latches engaging with said shifters to hold them depressed, trip-pawls pivoted thereon and actuated by a moving part of the device to throw said latches and restore the shifters to their normal position, and lugs on said latches engaging said pivoted trip-pawls.

11. The combination, in an electric transmitter, with a series of switch-shifters and of a set of latches engaging with said shifters to hold them depressed, trip-pawls pivoted thereon and actuated by a moving part of the device to throw said latches and restore the shifters to their normal position, said latches being provided with lugs engaging said pivoted trip-pawls on either side.

12. The combination, in an electric transmitter, with the series of spring-pressed, switch-shifters, of a set of spring-pressed toggles extending between a fixed part and said switch-shifters to hold the latter depressed, and means for throwing said toggles to restore the shifters to their normal position.

13. The combination with a rotating shaft, and with a series of circuit make and break rings thereon, of a set of shifters for controlling said rings, a set of contact-pieces engaging said rings, and springs extending between said shifters and said contact-pieces.

14. The combination with a series of movable contact-surfaces, of a set of shifters controlling the movement of said surfaces, a set of brushes engaging said surfaces and springs between said brushes and said shifters.

15. The combination with a rotating shaft, and with a series of circuit make and break rings thereon, of a set of shifters for controlling said rings, a pair of contact-pieces, loosely connected together engaging each of said rings, and springs between each pair of contact-pieces and the shifter corresponding thereto.

16. The combination with a rotating shaft and with a series of circuit make and break rings thereon, of a set of shifters having curved seats or depressions for supporting said rings, and insulating-strips secured to said shifters on one side of said seats or depressions and extending between the rings.

17. The combination with a rotating shaft and with a series of circuit make and break rings thereon, of a set of contact-pieces engaging said rings, and insulating-strips secured to said contact-pieces and extending between said rings.

18. The combination with a rotating shaft, and with a series of circuit make and break rings thereon, of a set of shifters for controlling said rings, a set of contact-pieces engaging said rings, and insulating-pieces secured to said shifters and to said contact-pieces and extending between the rings.

19. The combination with the frame of a type-writer, of a transmitter-frame, a series

- of finger-keys, switch-shifters and type-bars corresponding thereto, pivoted supplemental levers operatively connected to said type-bars, offsets on said finger-keys engaging said supplementary levers, a throw-off common to the fulcra of the supplementary levers to disengage them from said offsets, and connectors pivoted to said finger-keys and engaging said switch-shifters.
10. The combination in a combined typewriter and transmitter, of the individual pivoted finger-keys, the series of type-bars and switch-shifters, corresponding thereto, the set of pivoted supplemental levers connected by links with said type-bars, offsets on said finger-keys provided with notches engaging pins secured to said supplemental levers, connectors pivoted to said finger-keys and having offsets engaging said switch-shifters, a
- 15 throw-off common to the fulcra of said supplemental levers for bodily moving the same

to disengage said pins from said notches, and a second throw-off common to said connectors to cast the same at will and free the shifters from the keys.

25

21. The combination in a combined typewriter and transmitter, of the individual finger-keys, the series of type-bars and switch-shifters corresponding thereto, the set of pivoted supplemental levers operatively connected to said type-bars, connections intermediate said finger-keys and said supplemental levers and intermediate said finger-keys and said switch-shifters, a throw-off common to the fulcra of said supplemental levers for disengaging the same from said connections, and a second throw-off arranged to free said shifters from said connections.
